COIN DELIVERY CHUTE

Louis C. Galoich, Chicago, Ill., assignor to
 Coinometer Corporation, Chicago, Ill., a corporation of Illinois

Application December 19, 1949, Serial No. 133,863

4 Claims. (Cl. 193—23)

1

This invention relates to a new and useful improvement in a coin delivery chute and more particularly to a coin delivery chute with flexible walls which permit positioning of a delivery spout in different directions relative to a coin delivery machine.

Devices for delivering change to customers are used extensively in theaters, restaurants, and other business establishments. These devices usually consist of a coin delivery machine with a coin delivery chute attached thereto. A delivery cup receives the coins from the delivery chute and the customer removes his change from the delivery cup.

Since the number of places where such devices are used is quite numerous, it is desirable that a system be presented whereby the direction and position of the delivery chute relative to the coin delivery machine is variable. Furthermore, since the coin delivery chute may be located at different sides of the coin making machine, it is desirable that a chute be provided which may be simply and easily connected to and disconnected from the coin delivery machine.

Thus, one of the objects of this invention is to provide a flexible coin delivery chute which may be quickly and easily mounted outside the coin delivery machine.

Another object of this invention is to provide a coin delivery unit with flexible walls which permit of variable positioning and which is connected wholly outside of the coin delivery machine to which it is connected.

A further object of this invention is to provide a coin delivery unit with flexible walls which permit variable positioning of the coin delivery cup and in which all the parts are mounted as a unit outside the coin delivery machine.

Further objects and advantages of this invention will become apparent as the following description proceeds and the features of novelty which characterize this invention will be pointed out with particularity in the claims annexed to and forming part of this specification.

A preferred embodiment of the invention is shown in the accompanying drawing, in which—

Figure 1 is a side view, partly in section, of the improved coin delivery chute;

Figure 2 is a plan view taken on the line 2—2 of Figure 1 showing in dotted views the coin delivery chute swung into different positions;

Figure 3 is a view of the mounting plate taken substantially on the line 3—3 of Figure 1;

Figure 4 is a bottom view of connection between the flexible walls and the spout taken on the line 4—4 of Figure 1;

2

Figure 5 is a cross-section view of the flexible walls and the spout walls taken on the line 5—5 of Figure 1; and

Figure 6 is a side view of one of the flexible walls.

Referring to Figures 1, 2 and 3 there is shown a mounting plate 11 adapted to be secured to the exterior of a coin delivery machine (not shown). The mounting plate 11 has a rectangular opening 12 therethrough which registers with a similar coin delivery opening (not shown) in the coin delivery machine. The coin delivery openings in these coin delivery machines are of standard design and need not be shown. The means for securing the mounting plate 11 to the coin delivery machine are also standard and are shown in Figure 3. These means consist of three mounting members, usually screws, extending from the coin delivery machine over which the mounting plate 11 is hooked. A pair of open ended cut outs 13 at the bottom of mounting plate 11 fit over the shanks of two of the screws. A third cut out 14 is provided for also engaging the shank of a mounting screw and the enlarged portion 15 of cut out 14 permits passage of the head of the mounting screw through the mounting plate 11. The heads 16 of the mounting screws are shown in Figure 3.

The mounting plate 11 has a face 17 abutting the coin delivery machine and an outer face 18. A supporting bracket 19 is mounted on the outer face 18 by means of screws 20. Supporting bracket 19 is located beneath opening 12 in mounting plate 11. A pair of vertical ears 21 bound the vertical sides of rectangular opening 12. A hood 22 is also mounted on the outer face 18 of mounting plate 11 and is secured to plate 11 by means of screws 23.

In the regular construction of a coin delivery machine a portion of the coin delivery chute in the machine extends outside of the machine through the coin delivery opening. The base portion 24 of the extended end of the machine chute is shown in Figure 1. A coin 25 being delivered is also shown just before it leaves the machine chute. The coin rolls down the chute in this type of machine.

Referring back to the machine constituting this invention, the coin delivery chute is shown having a flexible chute section 26 and a spout section 27. Chute section 26 and spout section 27 have a single base member 28. Base member 28 has a rounded disc portion 29 and an elongated sloping portion 30. A threaded stud 31 is secured to the bottom side of rounded disc portion 29. Stud 31 is located in the center of disc portion 29. Stud

31 also extends through hole 32 in bracket 19 thereby pivotally mounting base member 28 on bracket 19. A wing nut 33 on threaded stud 31 cooperates with a lock washer 34 to clamp base member 28 in a fixed position.

The spout section 27 has a pair of sheet metal wall members 35. These wall members 35 are secured to sloping portion 30 of base member 28 by means of screws 35a. A portion of the top edge of each wall member 35 is bent over to form a downwardly extending flap 36. This downwardly extending flap 36 is parallel to the adjacent wall and is spaced from the wall to form a slot-like guideway 37. A portion of the bottom edge of each wall member 35 is crimped at 38 so as to form a wall 39 spaced from the base member 28. The wall 39 and base member 28 form therebetween a slotted passageway 40.

The flexible chute section 26 consists of a pair of flexible sheet metal walls 41. Each flexible wall 41 is clamped in position against between an ear 21 and a clamping strip 42 by means of screws 43. The bottom edge 44 of flexible wall 41 follows in general the contour of base member 28. Thus bottom edge 44 has a horizontal run 45, which lies adjacent disc portion 29, and a sloping run 46 which lies adjacent sloping portion 30. Extending downward from the lower edge 44 of the extended end of flexible wall 41 is a finger or flap 47. Finger 47 is inserted into slotted passageway 40 to serve as a means for restraining the flexible wall 41 against the corresponding spout wall. The top sloping edge 48 of flexible wall 41 is inserted in guideway 37. There flap 36 also restrains flexible wall 41 against the corresponding spout wall. The crimped sections 38 bounding slotted passageway 40 also serve to limit the motion of the flexible wall 41 relative to the spout walls 35.

A delivery cup 49 is secured to the extended end of the spout by means of a screw 50. The inside contour of delivery cup 49 is formed in the manner shown in Figure 2 so as to direct the rolling coins toward the side of the cup thus preventing the coins from jumping over the edge of the cup.

In operation, the wing nut 33 is unscrewed until the base member 28 is free to pivot around stud 31. The spout 27 and cup 49 are swung to the desired position, as shown in Figure 2, by bending the flexible walls 41 of chute section 26. Then the wing nut 33 is tightened up until the base member 28 remains in the desired position. When the wing nut 33 is unscrewed, the bent flexible walls 41 will swing the spout 27 and cup 49 back to the normal position. It will be appreciated that as the flexible walls 41 are bent, one wall 41 will move in one direction relative to its adjacent spout wall 35 while the other wall 41 moves in the opposite direction relative to its adjacent spout wall 35.

While there has been shown and described a particular embodiment of this invention, it will be obvious to those skilled in the art that various changes and modifications may be made therein without departing from the invention and, therefore, it is intended in the appended claims to cover all such changes and modifications as fall within the true spirit and scope of the invention.

What I claim as new and desire to secure by Letters Patent of the United States is:

1. A coin delivery chute for use with a coin delivery machine having a coin delivery opening therein, said coin delivery chute comprising a mounting plate adapted to be secured to the exterior of said machine, said mounting plate hav-

ing an opening therethrough adapted to register with said coin delivery opening, a bracket secured to said mounting plate, a spout pivotally mounted on said bracket, said spout comprising a base section and a pair of upright wall sections, a downwardly extending restraining member secured to the top edge of each wall section and extending parallel to the adjacent wall section in closely spaced relation to form a slot-like guideway therebetween, a portion of the lower edge of each wall section being spaced from the base section to form therebetween a slotted passageway, flexible strips secured at one end to said mounting plate and adjacent the opening therethrough, said flexible strips entering the slot-like guideways where they are positioned adjacent the upright wall sections, each said flexible strip having a downwardly extending finger at the lower edge positioned in the slotted passageways for further positioning the strips adjacent the upright walls, and the ends of each slotted passageway adapted to engage said downwardly extending finger to limit the pivoting of said spout.

2. A coin delivery chute for use with a coin delivery machine having a coin delivery opening therein, said coin delivery chute comprising a mounting plate adapted to be secured to the exterior of said machine, said mounting plate having an opening therethrough adapted to register with said coin delivery opening, a bracket secured to said mounting plate, a spout pivotally mounted on said bracket, said spout comprising a base section and a pair of upright wall sections, a portion of the top edge of each wall section being bent over to a position parallel with the adjacent wall section and spaced therefrom to form a slot-like guideway therebetween, a portion of the lower edge of each wall section being spaced from the base section to form therebetween a slotted passageway, flexible strips secured at one end to said mounting plate and adjacent the opening therethrough, said flexible strips entering the slot-like guideways where they are positioned adjacent the upright wall sections, and each said flexible strip having a downwardly extending finger at the lower edge positioned in the slotted passageways for further securing the strips adjacent the upright walls, each said slotted passageway having length providing for the range of relative longitudinal motion of the finger therein during the pivoting of said spout.

3. A coin delivery chute for use with a coin delivery machine having a coin delivery opening therein, said coin delivery chute comprising a mounting plate adapted to be secured to the exterior of said machine, said mounting plate having an opening therethrough adapted to register with said coin delivery opening, a bracket secured to said mounting plate, a spout pivotally mounted on said bracket, said spout comprising a base section and a pair of upright wall sections, a portion of the lower edge of each wall section being spaced from the base section to form therebetween a slotted passageway, flexible strips secured at one end to said mounting plate at a point adjacent the opening therethrough, guide means mounted on said upright walls for receiving the extended ends of said flexible strips to position said flexible strips adjacent the upright walls, and each said flexible strip having a downwardly extending finger at the lower edge positioned in the slotted passageways for further positioning the strips adjacent the upright walls.

4. In a coin delivery chute for use with a coin delivery machine having a coin delivery opening

therein, wherein said coin delivery chute includes a mounting plate adapted to be secured to the exterior of said machine, said mounting plate having an opening therethrough adapted to register with said coin delivery opening, a bracket secured to said mounting plate, and a spout pivotally mounted on said bracket, said spout comprising a base section and a pair of upright walls; the improvement in said coin delivery chute comprising a portion of the lower edge of each wall being spaced from the base section to form a pair of slotted passageways, one each between said base and an adjacent wall, flexible strips secured at one end thereof to said mounting plate adjacent the opening therethrough, guide means mounted on said upright walls of the spout for receiving the extended ends of said flexible strips

5 to position said flexible strips adjacent said upright walls, said guide means providing for relative longitudinal motion between the flexible strips and the adjacent walls, and each said flexible strip having a downwardly extending finger at the lower edge positioned in the slotted passageway for further restraining the strips adjacent the upright walls.

LOUIS C. GALOICH.
